UNITED STATES PATENT OFFICE.

HARLEY HILL, OF ITHACA, NEW YORK.

WORK-SUPPORT.

1,056,100.

Specification of Letters Patent. Patented Mar. 18, 1913.

Application filed January 24, 1912. Serial No. 673,250.

To all whom it may concern:

Be it known that I, HARLEY HILL, a citizen of the United States of America, residing at Ithaca, in the county of Tompkins 5 and State of New York, have invented certain new and useful Improvements in Work-Supports, of which the following is a specification.

This invention relates to improvements in 10 work supports and is more especially designed for use by jewelers and engravers.

The principal object of the present invention is the provision of a holder in which the work to be operated upon may be easily 15 and securely positioned in such a manner as to be freely revolved so that access may be readily had to the several sides thereof.

A device is also provided which is simple 20 and easy to manufacture although at the same time possessing the required strength for all uses to which it is designed to be employed.

The device is especially adaptable for holding 25 finger rings which are to be engraved upon either the exterior or inner surface thereof and the holder frame is adapted to be positioned and secured in the ordinary bench vise employed in the trade or engraver's block.

With these general objects in view and others that will appear as the nature of the 30 invention is better understood, the device consists in the novel combination and arrangement of parts hereinafter fully described and illustrated in the accompanying drawings and pointed out in the appended 35 claims.

In the drawings forming a part of this 40 application and in which like numerals of reference designate corresponding parts throughout the several views, Figure 1 is a perspective view of the device, Fig. 2 is a transverse sectional view taken on line 2--2 of Fig. 1, Fig. 3 is a bottom plan view of 45 the device, and Fig. 4 is an enlarged detail view of a portion of the device.

Referring more specifically to the drawing, the main support for the device consists in the circular ring 10 which is mounted, 50 preferably integrally upon the substantially square block 11, which is adapted to be mounted in a bench vise by its insertion between and engagement with the clamping jaws thereof, it being obvious the device 55 may thus be positioned either vertically or horizontally with respect to the block 11, and with either side of the device facing the

operator. Said ring 10 is provided at the upper edge of the outer periphery thereof with an annular seat or shoulder 12, while 60 completely encircling said ring is a circular band or annulus 13 which is provided with an inner projecting flange 14 at the top thereof which is adapted to be seated upon said shoulder 12 when said ring and annulus are assembled.

Fitting within the annulus 13 is provided the spider member 15 preferably constructed of a single piece of metal and having three peripheral sections 16 equally spaced apart 70 through the centers of which are provided suitable hold-fast devices, such as screws 17 for securing the spider member to the annulus, while the spider and annulus are normally so positioned that the annular 75 shoulder 18 of the spider member loosely receives and retains the ring 10 therein with such a relative play between the parts that the combined spider and annulus are free to revolve upon the ring support 10. The said 80 spider member is also provided with three angularly equidistant inwardly extending radial abutments presenting three equidistant squared inner faces 19. Screw-threaded perforations 20 provided through said 85 abutments receive the clamping screws 21 which are thus positioned radially of the device. By the use of swivelly mounted bearing blocks or pads 22 upon the inner ends of the screws, this means is adapted for 90 securely holding therebetween such a member as a ring, as shown in Fig. 3, said screws being preferably provided with operating heads 23 which will thus be positioned within the protecting cages 24. At points 95 upon the inner periphery of what may be termed the reverse side of the annulus 13 registering with the interrupted portions of the spider, such edge is slightly beveled or curved, as at 25 to allow easier access to the 100 operating screw heads 23.

The outer periphery of the annulus is 105 preferably roughened for affording a better gripping surface for the hand in manipulating the device.

From the above description the operation of the device, it is believed will be apparent.

The work holder having been securely positioned for instance in a vertical plane in a bench vise with the face of the same shown 110 in Fig. 1 directly in front of the operator, a ready manipulation of the clamping screws 21 will readily position a ring or other member therein and upon which it is

desired to engrave or inscribe a name for instance upon the inner periphery thereof. Access may thus be had to the uninterrupted inner surface of the ring which is held between the blocks 22 which may be of any convenient form and suitably cushioned if desired and mounted by some form of swivel upon the clamping screws 21, so as to be free from rotation therewith. The revolving of the ring for the purpose of working upon different portions of the sides thereof is readily effected by a turning of the annulus 13 by the hand of the operator which results in a consequent revolution of the spider 16 and the ring 26 or other piece of work mounted therein.

While the forms of the invention herein set forth are believed to be the preferable embodiments thereof, it is nevertheless to be understood that changes may be made in form, proportion and minor details of construction without departing from the spirit and scope of the invention as specifically set forth in the accompanying claims.

Having thus fully described my invention and in what manner the same is designed for use, what I claim as new and desire to secure by Letters Patent of the United States is:

1. A device of the class described comprising a block member, a supporting ring integrally mounted on one side thereof, an annulus surrounding said support and a spider member positioned within said support, said annulus and spider member adapted to revolve upon said support.

2. A device of the class described comprising a block member, a supporting ring integrally mounted on one side thereof, an annulus surrounding said support, a spider member positioned within said support, said annulus and spider member adapted to revolve upon said support and a plurality of securing means between said annulus and spider.

3. A device of the class described comprising a block member, a supporting ring integrally mounted on one side thereof, an annulus surrounding said support, a spider member positioned within said support, said annulus and spider member adapted to revolve upon said support, a plurality of securing means between said annulus and spider, three angularly equidistant abutments provided upon said spider and a clamping screw carried by each of said abutments and adapted to engage the work to be operated upon.

4. A device of the class described comprising a block member, a circular supporting ring secured to one side of said member, an annulus surrounding said support and freely revoluble thereon, a spider member positioned within said support and freely

revoluble therein and coöperating shoulders provided upon said annulus and spider adapted for retaining the supporting ring therein.

5. A device of the class described comprising a block member, a circular supporting ring secured to one side of said member, an annulus surrounding said support and freely revoluble thereon, a spider member positioned within said support and freely revoluble therein, coöperating shoulders provided upon said annulus and spider adapted for retaining the supporting ring therein, securing means between said annulus and spider, three angularly equidistant abutments provided on said spider and a clamping screw mounted upon each abutment and arranged radially of said spider, annulus and support.

6. A device of the class described comprising a block member, a circular ring support secured to one side thereof, an outer peripheral annular shoulder provided upon said ring, an annulus surrounding said ring and freely revoluble thereon, an inwardly-projecting annular flange provided upon said annulus and adapted to engage said ring shoulder, a spider member positioned within said ring and securing said ring between the same and the annulus and securing means between said annulus and spider and the work clamping screws radially journaled within said spider.

7. A device of the class described comprising a block member, a circular ring support secured to one side thereof, an outer peripheral annular shoulder provided upon said ring, an annulus surrounding said ring and freely revoluble thereon, an inwardly-projecting annular flange provided upon said annulus and adapted to engage said ring shoulder, a spider member provided with an outer annular shoulder, said spider adapted to be positioned within said annulus and ring with said ring fitting said shoulder, said annulus and spider revolubly mounted upon said ring, securing means between said annulus and spider, radially angularly equidistant abutments carried by said spider, and having squared outer faces, clamping screws journaled through said faces, and radially arranged operating heads provided upon ends of said screws positioned within said abutments, the portions of the annulus periphery lying adjacent said abutments being inwardly-beveled.

In testimony whereof I affix my signature in presence of two witnesses.

HARLEY HILL.
